[57] CLAIM

The ornamental design for an adult pacification novelty, substantially as shown and described.

DESCRIPTION

FIG. 1 is a top, front right view in perspective of an adult pacification novelty showing my new design;
FIG. 2 is a front elevational view thereof;
FIG. 3 is a rear elevational view thereof;
FIG. 4 is a top, front right view in perspective, similar to FIG. 1 with the adult pacification novelty being shown in an open condition;
FIG. 5 is a left side elevational view thereof; and
FIG. 6 is a bottom plan view thereof.
